M. W. PRYOR

MACHINE FOR MAKING FIBER COMPOSITION

Filed Oct. 11, 1922

UNITED STATES PATENT OFFICE.

MILTON W. PRYOR, OF AKRON, OHIO, ASSIGNOR TO THE GOODYEAR TIRE & RUBBER COMPANY, OF AKRON, OHIO, A CORPORATION OF OHIO.

MACHINE FOR MAKING FIBER COMPOSITION.

Application filed October 11, 1922. Serial No. 593,928.

My invention pertains to a novel method of manufacturing fibrous material, and it also relates to a machine for procuring a uniform felted relation between the various 5 fibers.

One object of my invention is to provide a method by which the fibers are deposited upon a movable screen at a uniform rate over a considerable area. Another object 10 of my invention resides in removing any moisture in the material at a uniform rate. A still further object of my invention consists in providing a machine whereby the material may be moved over an area comprising a plurality of zones in which different and variable degrees of suction have 15 been established.

Heretofore, in the manufacture of various types of fibrous material, it has been customary to employ a machine of the Fourdrinier type, commonly used in the manufacture of paper, by means of which material is produced in a continuous sheet of any desired length and width. The material is 20 formed upon a moving belt by employing a suction producing apparatus by which the liquid in which the fibers are suspended is drawn through the belt so as to leave a deposition of fibers thereon. Owing to the 25 relatively high degree of suction employed over the entire area of the felt in the liquid there is a tendency for a relatively large proportion of the ultimate thickness of the fibrous material to be deposited upon the belt as soon as it moves into the range of 30 the suction producing apparatus. This results in a relatively large number of fibers being deposited upon the belt in an extremely short interval of time, thus interfering 35 with the proper felting or matting thereof. After the initial deposition of the fibers on the belt but a relatively small number of fibers are added during the remainder 40 of the movement of the belt over the suction producing apparatus.

By my invention I have obviated this difficulty by causing the belt to pass successively over a number of relatively narrow suction boxes, whereby the force of the suction to which the fibrous material is subjected is gradually increased as the belt moves along the suction producing unit. In this manner the fibers are deposited at substantially a uniform rate throughout the

entire movement of the belt over the successive boxes.

In the accompanying drawing, I have shown a machine of the Fourdrinier type which consists of a movable belt or carrier 1, composed of porous material, and which moves over a pulley member 2, through an inclined plane 3, over a pulley member 4, through a horizontal plane 5, over two idling pulleys 6 and back to pulley 2.

That portion of the belt 1, which is disposed within the inclined plane 3, constitutes a side wall of a tank 7, in which is disposed a quantity of fibers suspended in liquid. The liquid and the fibers are both admitted to the tank 7 together through a conduit 8, which communicates with a feeding device. Disposed in engagement with that portion of the belt 1 which lies in the inclined plane 3, is a suction producing device which consists of a plurality of units 9, each of which are connected to a main suction producing device 10 by means of pipes, or conduits, 11. The air is exhausted from the member 10 and the liquid in the tank 7 is then drawn through the belt 1 by reason of the fact that the pressure in the suction box units 9 is reduced materially below the atmospheric pressure.

As the belt moves in the direction indicated by the arrow 1^a it comes into contact with the suction box 12, the first of the units 9, which is connected to the chamber 10 by means of a relatively small pipe 13. The second unit 14, of the suction producing device, is of equal dimensions with the unit 12, but is connected to the chamber 10 by means of a pipe 15 which is larger than the pipe 13. In like manner, the remainder of the units 9 are connected to the chamber 10 by successively larger connecting pipes, but all present the same amount of surface to the inclined plane 3.

By reason of the fact that the entire surface of the various units 9 are substantially open permitting the passage of liquid therethrough, and as the force tending to draw the liquid through the various pipes is exactly the same, it will be obvious that with each of the various pipes 11 having liquid passing therethrough at exactly the same rate, a materially smaller quantity of liquid will pass through the pipe 13 than

through any of the larger pipes. Also, since the open area of the chamber 12 is exactly similar to that of the chamber 14, and since a materially smaller quantity of water is drawn therethrough, the degree of suction at the surface of the box 13 must be materially less than at the surface of the box 14. In like manner, it may be proven that the suction at the surface of the container 14 is less than that of any of the succeeding units engaged by the belt.

It will be apparent from the description that the material is subjected to a gradually increasing pressure as it moves up the inclined plane 3, which is necessary to cause the fibers to be deposited thereon at a uniform rate, as the mat on the belt becomes gradually thicker and less porous. On account of the fact that the deposition of the fibers occurs over the entire surface of the suction producing apparatus rather than over but a relatively small portion thereof, the felting is more gradual, and the time and the opportunity for the proper felting of the fibers is very great as compared with structures heretofore employed for similar purposes.

The pipes 11 are each provided with a valve 17 by means of which the flow of liquid through the various pipes, and therefore the degree of suction existing in each of the units 9, may be regulated at will.

After the material has been formed upon the belt 1 it is carried into the horizontal plane 5 in which it is subjected to a bath of cleaning or displacing fluid from a tank 18, by means of spraying devices 19. Opposite the spraying devices 19 and in engagement with the belt 1 is disposed a plurality of suction producing units 20, which are connected to the main suction tank 10 by means of pipes 21 of relatively different areas. The first of the devices 20, with which the belt comes in contact, has a materially smaller degree of suction established therein than has any of the succeeding chambers, so that the degree of suction to which the belt is subjected is gradually increased, as described in connection with the device 9.

I have found it desirable to gradually increase the force of the suction from 0 to 2½ pounds per square inch, in order to secure the best results.

If the fibers employed are provided with individual coatings of rubber, the device 18 may be employed to spray a precipitant or displacing agent thereon, or to spray on a vulcanizing agent, as may be desired.

While I have illustrated but a single form which my invention may assume and have described in detail, but a single application thereof, it will be apparent to those skilled in the art that it is not so limited, but that various minor modifications and changes may be made therein without departing from the spirit of my invention, or from the scope of the appended claims.

What I claim is:

1. A machine for making a fibrous material comprising a movable porous belt, means for supplying thereto a quantity of fibers suspended in a liquid, means for removing the liquid therefrom through said belt comprising a plurality of vacuum chambers adapted to be successively engaged by said belt and a spray device for displacing the suspending fluid.

2. A machine for making a fibrous material comprising a movable porous belt, means for supplying thereto a quantity of fibers suspended in a liquid, means for removing the liquid therefrom through said belt comprising a plurality of vacuum chambers having different degrees of vacuum established therein disposed in engagement with said belt, adapted to be successively engaged by any moving portion thereof, and means for thoroughly washing the suspending medium from the formed sheet.

3. A machine for making a fibrous material comprising a movable porous member adapted to pass through a tank, means for supplying to said tank a quantity of fibers suspended in a liquid, means for removing said liquid through said movable member comprising a plurality of vacuum chambers adapted to be engaged successively by said movable member while immersed and having different degrees of vacuum established therein, a plurality of vacuum chambers adapted to be engaged by said movable member after leaving said tank, and means for washing the fibrous composition.

In witness whereof, I have hereunto signed my name.

MILTON W. PRYOR.
